METHOD OF VACUUMIZING CONTAINERS

Edward M. Enkur, Baltimore, Md., assignor to
 Crown Cork & Seal Company, Inc., Baltimore,
 Md., a corporation of New York

Application June 4, 1938, Serial No. 211,875

4 Claims. (Cl. 226—82)

The present invention relates to a method for vacuumizing containers.

In vacuumizing containers, it has heretofore been the practice to use either a vacuum chamber and associated pump, or to obtain a vacuum by filling the head space of the container with steam, seal the container and then rely upon the condensation of the steam to establish a vacuum. The first mentioned system requires rather expensive apparatus, and the second system, involving steam condensation, is not altogether satisfactory as usually practiced because moisture is frequently left in the head space of the container after condensation has occurred. With many products, particularly food products, such moisture is extremely undesirable.

An important object of the present invention is to provide a method and apparatus for vacuumizing containers by expanding the air or other gas within the container head space so that a portion of such gas will be forced out of the container head space, leaving a vacuum condition when the remaining gas condenses or contracts to a normal state.

Another object of the invention is to provide an apparatus and method whereby the presence of moisture in the container after vacuumization will be entirely prevented.

A still further object of the invention is to provide a vacuumizing apparatus and method which is extremely simple but which nevertheless eliminates all of the principal difficulties of previous apparatus and methods.

Other objects and advantages of the invention will be apparent from the following specification and drawing.

The drawing is a side elevation, partly in vertical longitudinal section, of a machine embodying my apparatus invention.

The embodiment of the invention illustrated in the drawing involves the application of heat to a container top after the top has been loosely applied to a filled container. Such heating of the top causes the air within the head space of the container to be expanded so that a portion of such air is driven from the head space. The top is then sealed to the container with the result that when the air within the head space is subsequently cooled and thereby condensed or contracted to its normal state, there will be a vacuum condition within the head space.

In the drawing, the jars or other containers to be vacuumized are indicated at J, the container caps being designated by the letter C. The containers J are delivered to the infeed end of an

endless container supporting conveyor 5 by any suitable means, the containers having been filled to a suitable height before delivery to conveyor 5. A cap delivery chute 6 of usual construction is provided above the infeed end of the conveyor 5, suitable means being provided at the lower end, I of the chute so that the passage of a container J beneath the lower end of the chute will cause a cap to be removed and dropped to a loosely seated position upon the container mouth.

A steam chamber 8 extends over the central portion of the upper run of the supporting conveyor 5, this chamber having an opening 9 of such width and height that it will permit the entrance of containers positioned upon the conveyor. Chamber 8 is kept filled with steam issuing from jets in a steam line 10, the pressure of the steam in the line merely being sufficient to insure that the atmosphere within the chamber 8 is heated and thereby expanded. Chamber 8 may be heated for the same purpose by means other than free steam, for example, by means of closed steam coils or electric heaters.

In the embodiment of the apparatus shown in the drawing, a cap heating element 11 consisting of an endless metal link chain or belt is provided within the steam chamber 8, element 11 moving about spaced pulleys, driven in any suitable manner. The belt or chain is of such width that it will bear upon the entire surface of a cap and thus heat the full area of the latter. In order to heat the element 11, a steam header 12 is provided having jets facing the upper surface of the upper run of element 11, but it will be understood that this heating element may be an electric heater, or that a gas flame may be used. A pressure member or shoe 13 is positioned above the lower run of the element 11 to force this run downwardly, the pressure member being urged downwardly by resilient means, for example, a spring, not shown. The lower run of element 11 is preferably inclined slightly downwardly toward its outfeed end, or at least to the right hand portion of the pressure member 13, thereby insuring that a cap C, while still loosely positioned on a container mouth, will move for some distance with element 11 with the upper surface or portion of the cap in contact with the underside of the lower run of element 11 and that the cap will not be forced to fully seated or sealed position upon the container until it has been adequately heated, as hereinafter described, by the heating element 11.

A cap cooling element 14 of endless form is also provided over the upper run of the supporting

conveyor 5, the left hand or infeed end of this element extending into an outlet opening 15 of the steam chamber 8. Element 14 is supported upon pulleys or sprockets in a manner similar to the element 11 and is driven by any suitable means. The element 14 is also of sufficient width to have contact with the entire area of the top walls of the caps. A pressure member 16 is mounted above the lower run of the element 14 to hold the run downwardly, springs, not shown, preferably being provided to maintain the member 16 and the lower run of element 14 downwardly. The lower run of element 14 and pressure member 16 are so arranged with respect to supporting conveyor 5 that a container cap C will be forced to or held in fully seated or sealed position upon a container J from a moment shortly after contacting with element 14, and will be held in such sealed position until it reaches the outfeed end of element 14. It is to be emphasized that a cap must be in fully seated and sealed position upon a container from a time prior to the egress of the cap and container from chamber 8, until the cap has been cooled sufficiently to obtain the condensing or contracting action hereinafter referred to.

In order to obtain a quick cooling of a cap by cooling element 14, a spray of cooling water is directed from a water line 17 upon the upper surface of the pressure member or shoe 16, and also upon the lower run of the endless element 14 to keep the same cooled over its portion exteriorly of the steam chamber 8. It will be obvious that means other than a water line may be used for the necessary cooling.

In the carrying out of the method by the apparatus illustrated in the drawing, when a cap C, loosely seated upon the mouth of a container J, is moved beneath the heating element 11, the cap, at least, will be quickly heated to such a degree that the air or other gas within the interior of the cap, that is, within the head space of the container, as well as the atmosphere immediately adjacent the cap and upper portion of the container, will be expanded to the desired degree.

Continuing its movement with the elements 5 and 11, the container will come beneath the lowermost portion of the bottom run of element 11 and the cap C will be forced to fully seated or sealed position on the container. When the container leaves element 11 and moves to the position indicated at J', that is, a position between the outlet end of the cap heating element 11 and the inlet end of the cap cooling element 14, if the internal pressure resulting from the expansion of air or other gas in the head space of the container is so high as to prevent the cap from remaining in completely sealed position upon the container, the cap will be slightly lifted by such pressure, and the surplus pressure will be expelled from the head space. This snifting action will, of course, leave the top space of the container filled with highly heated and expanded air or other gas. The presence of steam or other rarefied or expanded atmosphere in chamber 8, that is, at a point surrounding the upper portion of the container, will prevent air at atmospheric pressure from flowing into the head space of the container during or just after venting.

In some instances, the air at normal temperature or normal pressure originally within the head space of the container may be expanded to such a degree by heating element 11, and before

reaching the lowermost portion of this element, that the only expulsion of air or other gas from the head space of the container will occur prior to the movement of the cap to sealed position by the element 11, or at least simultaneously with the movement of the cap to such position. In these instances, the cap will remain in sealed position upon the container during the remainder of the movement of the container beneath the element 11, during its movement between elements 11 and 14, and also during movement beneath the cap cooling element 14. Thus, in such instances, the element 14 will function as a sealing element as well as a heating element.

In any event, it will be understood from the above that the point of expulsion of surplus expanded air or gas from the container head space can be controlled as desired by regulating the degree of heat applied to the top wall of the container, and that snifting, e. g., the expulsion of surplus expanded air, will occur whenever the air or gas in the head space of the container has been expanded to such an extent as to overcome the pressure existing outside of the container and immediately adjacent thereto, and if at that moment the cap is free to slightly lift.

During travel beneath cooling element 14, the air or other gas within the head space of the container will of course be condensed or contracted, with the result that the pressure within the head space of the container will be substantially less than atmospheric pressure. This vacuum condition will serve to hold the container cap in firmly seated and sealed position upon the container mouth. It will be understood that as a vacuum condition is being established within the head space, the cap will be drawn to a sealed position.

Obviously, when a container sniffs at point J', that is, a point between elements 11 and 14, element 14 serves as a sealing element as well as a hold-down or cooling element. The infeed end of the element 14 is positioned within the steam chamber 8 so that if a cap has lifted by snifting action adjacent point J', it will again be moved to sealed position with respect to its container by the element 14 before passing out into the atmosphere through the exit opening 15 of chamber 8. Thus, the entire portion of the path of travel of a container during which snifting may occur is surrounded by an expanded or rarefied or steam atmosphere, as by the steam chamber 8, and the element 14 is so positioned with respect to the chamber and also the container supporting conveyor 5 that cap C will be in securely seated and sealed position upon a container at the time that it leaves the steam chamber 8 beneath the cooling element 14.

The positioning of the cooling means 17 above the lower run of the element 14 will insure that the fabric or flat metal links or other cap contacting members of which the element may be formed will be cooled immediately after leaving the steam chamber 8, and that the temperature of the lower run of the element will be progressively reduced by the cooling spray or other cooling means as it moves away from the steam chamber outlet 15. Also, the cap holding and cooling element 14 will have its lower run of such length that all air or other gas within the head space of a container J will be condensed or contracted before the container moves from beneath the right hand or outlet end of element 14.

If steam, as from the line 10, is used to provide a heated or otherwise expanded or rarefied atmosphere within the chamber 8, the free steam within the chamber will only provide sufficient pressure to prevent entrance of air into the chamber through the chamber openings 9 and 15. Hence no steam will move into the head space of a container and the presence of free moisture within the head space of a container sealed by the present method and apparatus will be entirely avoided.

The caps to be used with the method and apparatus of the present invention may be of a number of well-known types. Generally speaking, any cap of such design that it will be held firmly seated and sealed by a vacuum condition in the container head space gives highly satisfactory results, and if conditions are so regulated that shifting will occur prior to sealing the cap by the heating element 11, the invention may be practiced with a cap of the type wherein retaining means, alone, is relied upon to maintain the cap seated and sealed. The caps must be of a material having reasonably high heat conductivity, though in some instances the method may be practiced by heating a portion of the container body, and in such case, heat conductivity of the container material may be relied upon.

The phraseology used in the specification is for the purpose of description and is not intended to limit the invention, the scope of the invention being indicated in the claims.

I claim:

1. A method of vacuumizing a filled container comprising applying a dry cap loosely to the container, moving the container and applied cap into a steam chamber, immediately applying local dry heat to the cap to expand the head space air before it can become moist and so that at

least a portion of the head space air will be quickly expelled, the local heating being continued during movement through the steam atmosphere to prevent access of steam to the head space, and sealing the cap upon the container.

2. A method of vacuumizing a filled container comprising applying a dry cap loosely to the container, moving the container and applied cap into a rarefied atmosphere, applying local dry heat to the cap to create higher pressure and temperature conditions within the head space than exist in the surrounding rarefied atmosphere so that at least a part of the head space gas will be expelled into the surrounding rarefied atmosphere, and sealing the cap upon the container.

3. A method of vacuumizing a filled container comprising applying a dry cap loosely to the container, moving the container and applied cap into a rarefied atmosphere, applying local dry heat to the cap to create higher pressure and temperature conditions within the head space than exist in the surrounding rarefied atmosphere so that at least a part of the head space gas will be expelled into the surrounding rarefied atmosphere, and then sealing the cap upon the container and cooling the head space.

4. A method of vacuumizing a filled container comprising applying a dry cap loosely to the container, moving the container and applied cap into a heated chamber, applying sufficient local dry heat to the cap to heat the head space to a temperature above that of the product within the container and above the temperature of the chamber so that the pressure within the head space will be increased and at least a portion of the head space gas will be expelled, and sealing the cap upon the container.

EDWARD M. ENKUR.
